UNITED STATES PATENT OFFICE.

LINCOLN BRODT, OF WEST BERKELEY, CALIFORNIA.

SEPARABLE SQUARE.

981,372.

Specification of Letters Patent. Patented Jan. 10, 1911.

Application filed December 16, 1909. Serial No. 533,384.

To all whom it may concern:

Be it known that I, LINCOLN BRODT, a citizen of the United States, residing at West Berkeley, in the county of Alameda and State of California, have invented new and useful Improvements in Separable Squares, of which the following is a specification.

My invention relates to improvements in squares for the use of carpenters and mechanics. Its object is to provide a strong, accurate, practical separable square, simple in construction, which can be manufactured and sold practically at the same price as any one-piece square; and which improved square, when interlocked, will be perfectly rigid, with its opposite surfaces flat and flush at the joint, so there will be nothing to interfere with the square's lying perfectly flat the same as an ordinary square. Particularly I have designed a square with interlocking means whereby friction and wear are entirely eliminated, and which may be subjected to any sort of rough usage without the square's being loosened or getting out of true.

The invention consists of the parts and the construction and combination of parts as hereinafter more fully described and claimed, having reference to the accompanying drawings, in which—

Figure 1 is a perspective of the separated arms. Fig. 2 is a partial central longitudinal section of the arm A. Fig. 3 is a perspective of the wedge members. Fig. 4 is a plan of a portion of the square.

In the embodiment of the invention as put to actual use, and as shown in the drawings, A and B represent two separable arms of suitable size and construction and suitably graduated in a manner well known in the art. The invention resides in the interlocking means for these arms. One arm, as B, is slightly reduced at the end, as shown at 2, there being a part cut out from one side corresponding to a ledge 3 on the opposite arm A; the reduced portion 2 being slotted, as shown at 4, so as to fit the tongue 5 on arm A, this tongue portion having a thickness equal to the width of the slot, and the length of the tongue being equal to the width of the slotted end 2, so that the two parts will have a snug, sliding interlocking fit.

When the two arms are put together they will stand approximately at right angles to

each other, and a diamond-shaped or ovoidal hole 6 in the end 2 will just register with a corresponding hole 7 in the tongue 5. Both sides of the end 2 are made with 60 similar holes 6, and the walls of these holes are beveled oppositely and outwardly, as shown at 8, while the hole 7 in tongue 5 has its walls straight across, as shown in Fig. 1. These double-ended oppositely tapered 65 holes 6—7 are important, as are likewise the tapered wedges 9 which are adapted to fit these holes and to be expanded one from the other to clamp and bind the arms A and B together and maintain them rigidly and 70 fixedly in right angle position.

The wedge members 9 are connected by the right and left threaded screw 10 which is perforated at 11 to receive a nail or like instrument whereby it may be rotated to 75 draw the wedges 9 toward, or force them from, each other. When the wedges 9 are drawn inwardly toward each other, and the arms A and B are slipped together so as to bring the holes 6—7 into register, the wedges 80 can be slipped into the holes, and then by turning the screw 10 in the proper direction the wedges 9 are forced outwardly from each other into the wedge-shaped ends of the slots 6—7. The wedges are each grooved, as 85 shown at 12, on their opposite sides, these grooves having a flat bottom and inwardly beveled walls 13, as shown. These beveled walls 13 on one side of the wedges are adapted to coact with the beveled walls 8 90 on that side of the holes 6 in arm B, while the flat bottom of the grooves 12 on the opposite side of the wedges are adapted to coact with the corresponding wall of the slot 7 in arm A. Consequently when the 95 screw 10 is rotated to expand the wedges it will have a drawing effect on the arm B transversely of arm A, so as to bring the bottom 4^a of slot 4 snug up against the flat straight edge portion 5^a of the tongue 5. 100 Thus it will be seen that the wedges have a double draw, with two points of bearing on one side of the wedge, to-wit, against the inclined faces 8, as shown in Fig. 2, and one point of bearing on the opposite 105 side of the wedges, to-wit, against the corresponding wall of slot 7 in tongue 5. Consequently there is no friction and no wear between the joints of the square. Also, this three-point bearing of the two sections, produced by the beveled walls 3—13—8 and 110 straight bottom of slot 12 against the straight

2
wall of tongue 5, produces a pinching action on the ends of the forked end 2, to press these ends together and so hold them tight and flush against that edge of the square at 5 all times; this pinching action being represented by the arrows 14. Furthermore, the lateral end guide 3 on member A is adapted to support and give rigidity to the corresponding edge of the reduced end 2 10 of member B.

By fashioning the apertures 6—7 and the double-ended expandible wedge in the manner shown, the drawing action by the wedge is exerted directly at right angles to the 15 tongued member A of the square, and the pull is distributed practically over the full length of the apertures 6—7, so that a broad firm seat and bearing are provided for one member against the other.

20 Having thus described my invention, what I claim and desire to secure by Letters Patent is—

1. A square comprising two separable members, one of which is grooved at one 25 end in the plane of the member, the other member having a corresponding tongue to fit the groove, said tongued and grooved portions co-incidentally apertured, said apertures being wider at the center than at 30 the ends and having similar ends, and an expandible wedge member formed of two similar parts with their bases presented toward each other, the parts of said wedge

member fitting corresponding parts of the apertures.

2. A square comprising two separable members one of which is grooved at one end in the plane of the member, the other member having a corresponding tongue to fit the groove, said tongued and grooved portions co-incidentally apertured, said apertures being wider at the center than at the ends and having similar ends with the apertured portions relatively reversed, and a double-ended expandible member fitting 45 in said aperture, said expandible member comprising two relatively reversed but similar tapered parts with their edges grooved and with their bases presented toward each other, the walls of said grooves being beveled, and the walls of said apertures being correspondingly beveled whereby on the expansion of the wedge said wedge will have two points or lines of bearing on one side and against the grooved member of the 50 square and will have one point or line of bearing on the other side and against the tongue portion of the square.

In testimony whereof I have hereunto set my hand in the presence of two subscribing 55 witnesses.

LINCOLN BRODT.
